UNITED STATES PATENT OFFICE.

JAMES IRA FRIAR, OF PASCAGOULA, MISSISSIPPI.

ROTARY ENGINE.

SPECIFICATION forming part of Letters Patent No. 391,892, dated October 30, 1888.

Application filed January 10, 1888. Serial No. 260,281. (No model.)

To all whom it may concern:

Be it known that I, JAMES IRA FRIAR, of Pascagoula, in the county of Jackson and State of Mississippi, have invented a new and Improved 5 Rotary Engine, of which the following is a full, clear, and exact description.

The object of my invention is to provide a new and improved rotary engine which is simple and durable in construction and utilizes 10 the steam to the fullest advantage.

The invention consists in the construction and arrangement of certain parts and details and combinations of the same, as will be fully 15 described hereinafter, and then pointed out in the claims.

Reference is to be had to the accompanying drawings, forming a part of this specification, in which similar letters of reference indicate 20 corresponding parts in all the figures.

Figure 1 is a side elevation of my improvement. Fig. 2 is a vertical cross-section of the same on the line *xx* of Fig. 1. Fig. 3 is a vertical sectional elevation of the same on the line *yy* of Fig. 2. Fig. 4 is a plan view of the 25 valve-seat, and Fig. 5 is a plan view of the steam partition-head. Fig. 6 is an enlarged transverse sectional elevation of the gate and packing on the line *zz* in Fig. 7, and Fig. 7 is a sectional side elevation of the same on the 30 line *yy* of Fig. 2.

My improved rotary engine is provided with a cylinder, A, consisting of the central part, B, having on its lower end a base, by which the entire engine is supported on a suitable 35 foundation. The central part, B, is covered at each side with part of a ring or annular plate, C or C', which plates are alike in construction and form in conjunction with the central part, B, the steam space D. The top 40 part of the cylinder A is straight, as illustrated in Fig. 1, and supports the valve-seat E, on which is secured a steam-chest, F, provided with the steam-inlet F', and also containing a double slide-valve, G, secured to a valve-rod, G', pivotally connected with a lever, H, fulcrumed on a bracket, H', secured to the cylinder A. By moving the lever H forward or backward I am enabled to shift the slide-valve G on its seat E. The latter is provided with 45 the two steam-inlet ports *a* and *b*, connecting the steam-chest F with the space D, formed in the cylinder A, on each side of the two down-

wardly-extending lugs E', secured to the valve-seat E. The latter is also provided with the exhaust-ports *c* and *d*, which extend a short 55 distance from the top into the seat E, and both open at one end into a channel, *e*, leading to the exhaust-pipe secured in any suitable manner in the outer side of the valve-seat E. The ports *a* and *c* can be connected with each other 60 by the cavity G², formed in the under side of the slide-valve G, and the ports *b* and *d* can be similarly connected with each other by the cavity G³, also formed in the under side of the slide-valve G. Between the cavities G² and G³ 65 are formed the ports *f* and *g* in the slide-valve G, and adapted to connect alternately with the steam-inlet ports *a* and *b*, so as to admit steam from the steam-chest F into the space D in the cylinder A.

In the cylinder A is held to rotate a piston, I, secured to the shaft J, fastened in the center of said piston and mounted in suitable bearings on each side of the cylinder A, being also connected in any suitable manner with the machinery to be driven. The piston I is preferably made in two parts, K and L, united by radial webs and bolts, as shown in the drawings, of which the part K is the central one, being secured to the main driving-shaft 75 J, and being provided with three radial slots, K'. The other part, L, of the piston I is ring-shaped, and is provided with three stuffing-boxes, L', fitting with their openings over the slots K' in the central part, K. In said slots 80 K' in the stuffing-boxes L' are held to slide radially the gates N, each provided at its inner end on each edge with a friction-roller, O, fitting into a cam-groove, P', formed in a cam, P, secured to each side of the cylinder A. The 85 lower part of the cam-groove P' is circular, having its center on the axis of the shaft J; but the upper part of said cam-groove P' is eccentric, as shown in Fig. 1. When the friction-rollers O enter and pass through the circular parts of the cam grooves P', the gates N are respectively moved outward to the fullest extent and completely cover the interior space, D; but when the friction-rollers O pass from the semicircular parts of the cam-grooves P' 90 into the eccentric upper parts the gates N are alternately drawn inward until they are flush with the rim part L of the piston I, which takes place when a gate N stands in the vertical po- 95 100

sition in the center of the machine, as shown in Fig. 1. The rotary movement of the piston I then causes the friction-rollers O as they pass again into the semicircular parts of the cam-grooves to move the gate N outward until it again intersects with the circular part of the groove P', whereby the gate is again drawn out to its fullest extent.

In the middle of the under side of the valve-seat E a cavity is formed between the downwardly-extending lugs E', above mentioned, and in this cavity is placed a steam partition-head, Q, provided on top with a recess, Q', formed by the L-shaped plates Q², arranged, as shown in Fig. 5, so that when steam is admitted into said cavity Q said plates Q² are pressed outward in tight contact with the walls forming the central opening in the valve-seat E. Steam is admitted to this central opening, Q', by a port, E², in the valve-seat E, leading to said cavity, and said port E² always registers with a port, G⁴, formed in the middle of the slide-valve G.

In order to establish a steam-tight joint between the rings C and C' of the cylinder A and the rim part L of the piston I, I form a circular groove at the respective intersections of the rings C C' and the ring L, and place in said groove a metallic ring, R, on which is placed a packing, S, of any suitable material. On top of this packing in said groove is placed a second metallic ring, T, held in place by screws U, screwing in the clamps V, held in any suitable manner on the rings C and C', as illustrated in Fig. 2. I am enabled in this manner to adjust the rings S and T so as to prevent leakage of the steam from the space D to the outside.

Each of the gates N is provided at its sides, near the top, with the openings N', leading to recesses N², formed in the gate, and each recess contains two L-shaped plates, N³, overlapping each other, as shown in Fig. 6. Each plate N³ is provided on its inner ends with an offset, N⁴, on which is held a spring, N⁵, resting with its free ends against a bar, N⁶, bolted to the ends and sides of the gate N at the inside of the recesses N². The outer ends of the L-shaped plates pass through the opening formed in the recesses N² between the central end part of the gate N and the said bars N⁶. When steam is admitted through the respective opening N' of one gate N, then the L-shaped plates are forced outward against the springs N⁵, which are consequently compressed, and the outer ends of the said bars are forced in contact with the rings C C' and the part B of the steam-space D in the cylinder A, thus forming a steam-tight packing between the cylinder A and the respective gate N. When the exhaust takes place, then the compressed springs N⁵ force the plates N³ inward and out of contact with the sides and rim of the space D of the cylinder A. The plates N³ are thus held out of contact with the sides and rim of the space D until the respective gate N reaches its full stroke and takes the pressure of the steam.

Thus the noise and consequent wear which would otherwise take place are prevented.

The operation is as follows: When the machine is in the position shown in Fig. 1, the slide-valve G registers with its port g with the steam-inlet port b, and the ports a and c are connected with each other by the cavity G², formed in the under side of the slide-valve E. The steam now enters from the steam-chest through the port g into the port b, and from the latter passes into the steam-space D, formed in the cylinder A at the right of the partition-head G, so that the steam exerts its pressure against the gate drawn out to its fullest extent by the friction-wheels O having just entered the circular part of the cam-groove P'. The piston I is thus forced to rotate in the direction of the arrow a', whereby the friction-wheels O travel in the cam-groove P', and thus enter alternately the circular part of the groove and the eccentric part of the groove, whereby the gates are drawn inward and outward, so that the steam entering through the ports above described always acts with its full pressure on the respective gate whenever it is drawn out to its fullest extent—that is, when the friction-rollers O enter the circular part of the cam-groove P'. When the friction-rollers O on the inner end of the gate reach the eccentric part of the cam groove P, then the steam in front of the extended gate N escapes out through the port a into the cavity G² in the slide-valve G and into the exhaust-port e, from which it passes into the channel e and out through the exhaust-pipe connected with said channel. Steam also enters from the steam-chest F through the port G⁴ into the port E² and into the cavity Q' of the partition-head Q, whereby said partition-head is pressed in contact with the rim of the part L of the piston I, and at the same time the L-shaped bars Q² are pressed outward in contact with the surrounding walls in the valve-seat E, so that no live steam can leak back from the steam-space D, and the exhaust-steam is also prevented from leaking forward into the live-steam part of the space D.

When the operator desires to reverse the engine, he throws the lever H inward toward the steam-chest F, so as to disconnect the ports g and b and connect the port f with the port a. At the same time the ports b and d are connected with each other by the cavity G³ in the under side of the slide-valve G. The steam now enters the port f and passes into the port a and to the left side of the compartment D, so that the steam now exerts its pressure against the respective gate N in the inverse direction of the arrow a'. The exhaust takes place through the port b, the cavity G², and the port d, from which the steam passes into the channel e and out through the exhaust-pipe.

It will be seen that the steam-tight packing is arranged at all the joints, so as to prevent leakage of the steam, and at the same time friction has been reduced to a great extent, so as to insure an easy running of the piston.

By forming the cylinder with a concentric longitudinal opening the heat of the steam is removed from the shaft and boxes a distance in proportion to the diameter of the engine, 5 and the trouble arising from hot boxes is obviated, and more power in proportion to the weight of the engine and boiler can be obtained by having this opening. For example, if I have a five-horse-power boiler and the work 10 requires a ten-horse power boiler, but circumstances will not allow of the usual weight of a boiler and engine of such sizes—for instance, where a portable hoisting-engine is required—I take a five-horse-power boiler and construct 15 an engine with the piston area of the five-horse-power engine, but with a diameter increased to the required dimensions to make it a ten-horse power. If the piston required three gates for a five-horse power to divide up the 20 cylinder so as to give the required cylinder-space to a given amount of fire box and grate-surface, and a ten-horse-power engine was to be run by a five-horse-power boiler, it would only be necessary to double the number of 25 gates in the piston, the space between each gate being the amount estimated upon.

It will be seen that by having the concentric longitudinal opening the weight of the engine would not increase in the same ratio, as the 30 weight of the valve, steam-chest, and thickness of the cylinder would remain the same, and the increase in weight by the above change would be about one-third, while the power would be doubled.

35 Having thus fully described my invention, I claim as new and desire to secure by Letters Patent—

1. In a rotary steam-engine, a cylinder having a concentric longitudinal opening and a cam held on said central opening at each side of said cylinder, in combination with a piston traveling in said central opening, and gates adapted to slide radially in said piston and carrying friction rollers traveling on said cam, 40 substantially as shown and described.

2. In a rotary steam-engine, a cylinder having a concentric longitudinal opening, a valve-seat held on top of said cylinder and provided with ports leading to said cylinder, a partition-head held in said valve-seat between said 50 ports, and a double valve held on said valve-seat to regulate the entrance and exhaust of the steam, in combination with a piston traveling in the central opening of the cylinder, 55 gates adapted to slide radially in said piston and into and out of said cylinder, and stationary cams held on said cylinder and engaged by friction-rollers on said gates, substantially as shown and described.

60 3. In a rotary steam-engine, a cylinder having a concentric longitudinal opening and cams supported on each side of said cylinder, in combination with a piston secured to the main shaft and traveling in the central opening of 65 said cylinder, gates adapted to slide radially in said piston, friction-rollers secured to the ends of said gates and traveling in the cam-

grooves of said cams, and packing-rings formed on said gates, substantially as shown and described.

70 4. In a rotary steam-engine, a cylinder having a concentric longitudinal opening and cams held on each side of said cylinder, and each provided with a cam-groove which is circular in its lower half and eccentric in its upper half, in combination with a piston made in two parts, of which the outer part is a ring fitting in the central opening in said cylinder, and the inner part is fastened on the main shaft, gates adapted to slide in radial grooves formed in 80 said piston, and friction-rollers secured to the ends of said gates and traveling in the cam-grooves of said cams, substantially as shown and described.

85 5. In a rotary engine, a cylinder having a concentric longitudinal opening, a piston fitted and rotating in said opening and provided with a radial gate, and a cam for operating the said gate, substantially as set forth.

90 6. In a rotary steam-engine, a cylinder having a concentric longitudinal opening, a piston fitting in said central opening and secured to the main shaft, and gates adapted to slide radially in said piston and into the said cylinder, in combination with a valve-seat held on top of said cylinder and provided with two 95 ports, a partition-head held in said valve-seat between said two ports, a steam-chest secured on top of said valve-seat, and a double valve held in said steam-chest on said valve-seat to regulate the admission and exhaust of steam, 100 substantially as shown and described.

105 7. In a rotary steam-engine, a cylinder having a concentric longitudinal opening, a piston fitting into said central opening, and gates adapted to slide radially in said piston and into 110 said cylinder, in combination with a valve-seat held on top of said cylinder and provided with inlet and outlet ports, a partition-head held in said valve-seat between said ports, a steam-chest secured on top of said valve-seat, a double valve held in said steam-chest and operating above said ports, and a valve-rod extending to the outside and adapted to be shifted in order to reverse the engine, substantially as shown and described.

115 8. In a rotary steam-engine, the combination, with a cylinder having a concentric longitudinal opening, a piston fitting in said central opening, gates adapted to slide radially in said piston, and said cylinder, of a valve-seat held on top of said cylinder and provided with steam inlet and outlet ports, and also provided with a central port, a partition-head held in the bottom of said valve-seat between 120 said first-named ports, said central port opening into said partition-head, a steam-chest held on top of said valve-seat, and a double valve operating in said steam-chest over said ports, so as to regulate the admission and exhaust of the steam to and from the cylinder, and also to admit steam to said partition-head, substantially as shown and described.

125 9. In a rotary steam-engine, the combina-

tion, with a cylinder, of gates held to slide in the said cylinder, and each provided on its sides with openings leading to a recess, L-shaped plates held to slide in the said recess and in contact with the said cylinder, and springs against which operate the said plates, substantially as shown and described.

10. In a rotary steam-engine, the combination, with a gate provided on each side with an opening leading to a recess, of L-shaped

plates held in each recess and overlapping each other, and springs held in said recesses and against which operate the said plates when forced outward by the action of steam entering the side opening of the gate, substantially as shown and described. 15
